Primary Examiner—Brian N. Vinson

(21) Appl. No.: **29/121,905**

(74) Attorney, Agent, or Firm—Angus C. Fox, III

(22) Filed: **Apr. 18, 2000**

CLAIM

(51) LOC (7) Cl. **06-04**

The ornamental design for a broom and tool holder mountable on a planar vertical surface, as shown and described.

(52) U.S. Cl. **D6/553**

DESCRIPTION

(58) **Field of Search** D6/553, 567; D8/367,
D8/349, 554, 373; 211/13.1, 70.6, 85.13,
65, 86, 88, 89.01; 248/309.1, 314

(56) **References Cited**

FIG. 1 is a top plan view of my new design for a broom and tool holder mountable on a vertical planar surface; FIG. 2 is a bottom plan view of the broom and tool holder; FIG. 3 is a front elevational view of the broom and tool holder;

FIG. 4 is a rear elevational view of the broom and tool holder; and,

FIG. 5 is right-side elevational view of the broom and tool holder, the left side elevational view thereof being a mirror image of the right-side elevational view.
